UNITED STATES PATENT OFFICE.

FREDERICK FRANCIS SCOTT, OF HILLISBURG, INDIANA.

RAILROAD-TIE.

SPECIFICATION forming part of Letters Patent No. 339,938, dated April 13, 1886.

Application filed February 18, 1886. Serial No. 192,361. (No model.)

To all whom it may concern:

Be it known that I, FREDERICK FRANCIS SCOTT, a citizen of the United States, residing at Hillisburg, in the county of Clinton and State of Indiana, have invented certain new and useful Improvements in Railroad-Ties; and I do hereby declare that the following is a full, clear, and exact description of the same, reference being had to the annexed drawings, making a part of this specification, and to the letters and figures of reference marked thereon.

Figure 1 of the drawings is a perspective view of my invention, and Fig. 2 a longitudinal section thereof.

The present invention has relation to certain new and useful improvements in railroad-ties; and it consists in the details of construction, substantially as shown in the drawings, and hereinafter described and claimed.

In the accompanying drawings, A represents the tie, and B the rails held thereon by the chair-sections C D, the former being cast with the tie and the latter sections connected thereto by bolts *a* and nuts *b*. These bolts extend up through the tie and chair-sections D, and the nuts *b* engage with the screw-threaded ends of said bolts, and are prevented from turning thereon by a longitudinal key, E, formed of spring metal. The key E has a dovetail head, *c*, to engage with a similarly-formed groove, *d*, in the upper side of the chair-sections D, and is inserted through the

end of the groove. The dovetail head *c* of the key E is so constructed with relation to the body of the key that when in position the key will assume an acute angle from a perpendicular in an outward direction, to prevent binding against the nuts, and also to enable it to be more conveniently inserted in place. The chair-sections C D overlap the feet of the rail B, and abut against the sides thereof between the feet and tread, and the rail is held firmly from longitudinal displacement by dowel-pins *e*, connected to the section D, and extending horizontally and transversely through holes in the rail and chair-section C.

Having now fully described my invention, what I claim as new, and desire to secure by Letters Patent, is—

A railroad-tie cast with chair-sections, as shown, in combination with similarly-formed chair-sections connected to the tie by bolts and nuts, a key provided with a dovetail head inserted in dovetail grooves in said chair-sections, the latter having dowel-pins extending through holes in the rail and holes in the opposite chair-sections, substantially as and for the purpose set forth.

In testimony that I claim the above I have hereunto subscribed my name in the presence of two witnesses.

FREDERICK FRANCIS SCOTT.
